UNITED STATES PATENT OFFICE.

HARRY RICHARD ANTCLIFF, OF BIRMINGHAM, ENGLAND.

LOCK.

SPECIFICATION forming part of Letters Patent No. 746,774, dated December 15, 1903.

Application filed May 4, 1903. Serial No. 155,655. (No model.)

To all whom it may concern.

Be it known that I, HARRY RICHARD ANTCLIFF, a subject of the King of Great Britain, residing at Birmingham, in the county of Warwick, England, have invented certain new and useful Improvements in Locks, of which the following is a specification.

This invention relates to locks.

The object of the invention is in a ready, simple, thoroughly feasible, and practical manner to render a lock non-pickable, the improvement being of such a character as to obviate any marked change in the structural arrangement of the lock, thereby reducing the cost of application of the improvement to a minimum and permitting it to be applied to locks already in use.

With these and other objects in view, as will appear as the nature of the invention is better understood, the same consists, generally stated, in making the keyhole an all-through solid-walled tubular passage separate from the mechanism of the lock and having a plurality of keyways arranged at the back of the lock to permit the key to be pulled back into and operate the wards or levers by turning the key in the usual manner. The keyways, which in this instance are shown as two in number in addition to the keyhole proper or entrance-keyway, are cut in the back plate of the lock in the form of slots, radiating at any convenient angle from each other, the said keyways being normally closed or protected by a curtain or disk operated and carried around by the key in a manner hereinafter described, so that when the key is manipulated to release the wards of the lock the supplemental keyways are sealed.

In the accompanying drawings, forming a part of this specification, and in which like characters of reference indicate corresponding parts, there is illustrated one form of embodiment of the invention capable of carrying the same into practical operation, it being understood that the elements therein exhibited may be varied or changed as to shape, proportion, and exact manner of assemblage without departing from the spirit thereof.

In the drawings, Figure 1 is a view in perspective of a lock embodying the improvements hereinafter described, the view being taken from the front of the lock. Fig. 2 is a

similar view taken from the rear side of the lock. Fig. 3 is a view in vertical section taken on the line $\alpha\alpha$ of Fig. 1. Fig. 4 is a vertical section taken on the same line as Fig. 3, exhibiting the key in its operative and inoperative positions. Fig. 5 is a compound view exhibiting in front and edge elevation the disk or curtain constituting the gist of the present invention.

Referring to the drawings, a designates the lock, which may be of any preferred construction and is provided with a solid-walled tubular keyhole or entrance-passage b , a continuation of which is formed by a hollow boss f' of the curtain or disk f , through which is formed a keyway to the back plate c of the lock. Cut in the said back plate and leading from and forming a connection with the exit end of the keyhole b are two radially-disposed slots d and d' , disposed at convenient angles to each other and constituting keyways or openings for the key e . The keyways d and d' are normally covered or sealed by the flange f of the curtain, which in this instance is shown as a disk, which flange bears against the inner face of the back plate c , the curtain being held against displacement by coaction between the flange and the back plate and the boss f' and the rear wall of the tubular passage b . The key e is provided with a collar e' , adapted to engage against the front plate g of the lock to limit its inward insertion; but it will be obvious that, if preferred, the said collar may be omitted without departing from the scope of the invention.

In operation to lock the lock the key is inserted through the keyhole b and through the curtain and is turned, together with the curtain, until the key comes opposite the opening d , whereupon it is partially withdrawn to permit the wards of the key properly to engage the tumblers of the lock, as indicated by dotted lines in Fig. 4. Upon the key being turned its wards actuate the tumblers, and when the tumblers are released the wards of the key are then opposite the keyway d' , whereupon the key is pushed inward to free the wards from the back plate c , and upon giving the key a further turn its wards are brought opposite the keyhole b , whereupon the key may be withdrawn. To unlock the lock the key is again inserted and turned in

the opposite direction, being pulled back into the keyway d' , and after releasing the tumblers it is pushed out through the keyway d and after being turned in the manner described is withdrawn through the keyhole b .

As there is only one keyway or opening in the curtain or disk, it follows that only one opening or keyway can be disclosed in the back plate of the lock at one time, and this renders the lock safe in use and practically non-pickable.

It will be seen from the foregoing that by providing a solid-walled tubular passage for a keyhole and by operating the lock from its back it is impossible to obtain direct access to the mechanism of the lock through the keyhole in the usual manner, so that tampering with a lock constructed in accordance with the present invention will be practically impossible.

Having thus described the invention, what I claim is—

1. A lock provided with a solid-walled tubular passage or keyhole, and having keyways or openings cut in its back plate, and a

curtain or disk provided with a single key way, and operated by the key, the keyways being so disposed as to communicate with the keyhole to permit the key to operate the locking mechanism.

2. A lock provided with an all-through solid-walled keyhole or passage, and with a plurality of keyways in its back plate radiating from the keyhole, and a curtain or disk movable by the key for protecting the keyways.

3. A lock provided with an all-through solid-walled keyhole or passage, and with a plurality of keyways in its back plate radiating from the keyhole, and a curtain or disk movable by the key for protecting the keyways, and having a single keyway.

In testimony whereof I have signed my name to this specification in the presence of two subscribing witnesses.

HARRY RICHARD ANTCLIFF.
